CONDIMENT DISPENSER

Joseph B. Stier, New York, N.Y.

Application October 6, 1958, Serial No. 52,875

Term of patent 14 years

(Cl. D44—22)

I claim:

The ornamental design for a condiment dispenser, substantially as shown.
